UNITED STATES PATENT OFFICE.

WILLIAM E. TALLCOT, OF CROTON LANDING, NEW YORK, ASSIGNOR OF
ONE-HALF TO HENRY H. UNDERHILL, OF SAME PLACE.

BRICK-MACHINE.

SPECIFICATION forming part of Letters Patent No. 237,636, dated February 8, 1881.

Application filed June 14, 1880. (No model.)

To all whom it may concern:

Be it known that I, WILLIAM E. TALLCOT, of Croton Landing, in the county of Westchester and State of New York, have invented a new and Improved Brick-Machine, of which the following is a specification.

The object of this invention is to increase the capacity, durability, and efficiency of a brick-machine.

10 The invention consists of a brick-machine provided with devices for preventing rupture of any of the parts of the machine by reason of stones or other obstacles becoming jammed in or about the press-box; of a device for preventing the escape of clay about the joints of the packer or plunger, and of other novel devices, all of which are hereinafter described.

Figure 1 is a side elevation of the machine. Fig. 2 is a front elevation of the same. Fig. 3 20 is a vertical sectional side elevation of the same on line xx , Figs. 2 and 4. Fig. 4 is a plan of the machine. Fig. 5 is a cross-section of the same on line yy , Fig. 3. Fig. 6 is a front vertical section on line zz , Fig. 3. Fig. 7 is a front elevation of the clod-cutter. Fig. 8 is a plan of the mouth-piece.

Similar letters of reference indicate corresponding parts.

In the drawings, A represents the base or 30 frame for supporting the mill-cylinder and machinery of the device, the legs A' A' being separated by arches A'' A'', and the said base A being strengthened by the arched ribs or flanges A''', that project over the arches A'' and down 35 the legs A' to the feet A'''' of the said base A.

B is the mill-cylinder, secured on the base or frame A by means of bolts a a, that pass through the several lugs b b' of the cylinder B and base A respectively. The said cylinder 40 B is composed of two semi-cylindrical sections, B' B', bolted together through their flanges c c, and in the rear of said cylinder B is a door, B'', whereby entrance may be had to the said cylinder B for the purpose of cleaning or re-pairing it.

Secured to the upper and rear edge of the cylinder B is a platform, B''', to facilitate the introduction of the brick material into the said cylinder B.

50 B'''' B''''' are side brackets formed upon the

cylinder B, near its top; and C C are upright standards or pillow-blocks, firmly secured upon said brackets B'''' by the bolts d.

Journaled in the boxes C' C' that are fixed on the faces of the pillow-blocks C C is the 55 horizontal shaft D, on one end of which is an eccentric, D', while on the opposite end thereof is a cog-wheel, D''.

Journaled in the boxes E E', on the tops of the standards or pillow-blocks C C, is the horizontal driving-shaft E, having on one end a cog-wheel, E'', that gears with the cog-wheel D'', and having also keyed upon it the bevel-gear wheel E''', that meshes with the crown-gear wheel F, which surmounts the top of the 60 vertical shaft F' of the mill-cylinder B, which shaft F' is stepped in an open thimble, f', which rests in a central opening in the base or frame A. Through this shaft F', within the cylinder B, the arms F'' are passed transversely, so as 65 to extend in equal lengths on opposite faces of said shaft F', from the top nearly to the bottom of the cylinder B, and so as to form on said opposite faces of the said shaft F' a quarter turn or spiral, as shown in Figs. 3 and 4. Within the cylinder B the shaft F' is enlarged, 70 in order to occupy more of the "dead" space, or space of least motion, within said cylinder B. Within the cylinder B the lower part of this shaft F' is provided on opposite faces with lateral lugs f f', through which pass the vertical 75 bolts f' f', on which are pivoted the curved sweeps or wipers G G, which revolve with the shaft F' and press into the press-box the clay or brick material that has been tempered by 80 the action of the arms F'', each wiper or sweep being secured independently of the other to the said shaft F' for convenience and economy of removal and repair. On the concave faces of these sweeps G G are attached the stops g g, 85 that bear against the shaft F' and support said sweeps G G against pressure of the clay. Said stops g g may be made parts of the sweeps G G, or may be made separately therefrom, and they may, if desired, be so arranged as to 90 yield and permit the sweeps G G to yield to excessive pressure within a rupturing strain.

G' G' represent bars, preferably of rectangular cross-section, that are passed horizontally and on different planes through the sides of 100

the cylinder B and fixed rigidly in place to co-operate with the arms F" in tempering the brick material.

G" represents the peripheral opening in the cylinder B, and near the bottom thereof, through which the tempered clay is pushed by the sweeps G into the press-box H through the openings h in the back of said box H.

H' H" are side flanges that are made parts 10 of the cylinder B, and extend forward on either side of the peripheral opening G", the front edges of said flanges H' H" being vertically channeled, as shown at k, to receive the back plate, H", of the press-box H, which back 15 plate, H", as it becomes worn by the friction of the clay on the front, can be readily removed and a new one substituted for it.

H''' H''' are the side plates of the press-box H, held to the flanges H' H' and over the edges 20 of the plate H" by the bolts l; and H'''' is the front plate, provided with slots l' on its edges, and held in position by bolts l'' that are pivoted on the lugs l''' on the outer faces of said 25 side plates, H''', and are secured by nuts in the said slots l'.

In the bottom of the press-box H is the clod-cutter I, consisting of a rectangular frame provided with transverse triangular bars m, with apices uppermost, set at a suitable distance 30 apart for the clay to be pressed between them into the mold M, which is provided with transverse partitions m', that form the brick-molds, and are adjusted centrally beneath said triangular bars m, so that, the width of the bars m being greater than the width of the partitions m' of the mold M, the clay will be delivered 35 and pressed into said mold M without rubbing the sand from the sides of said partitions m' as it enters the molds. The said mold M is also wider than the clod-cutter I, to prevent 40 the sand with which the said molds are dusted from being rubbed from the ends of said molds as the clay is pressed into them.

I' is a crenated plate forming the front of 45 the clod-cutter I, the teeth i of said plate I' resting against the ends of the triangular bars m, while the spaces i' are opposite the spaces between the bars m.

L is the mouth-piece of the said clod-cutter 50 I, extending across the front thereof and provided with rearward-projecting side lugs, L', the end of one of which rests in the catch of the spring L'', that is fastened vertically upon a flange, H', and has its forward pressure regulated by the adjusting-screw L''', which passes 55 through a lug, l''', on said flange H', and which spring L'' holds the said mouth-piece L closed, and said mouth-piece L is pivoted on the bolts L'' that enter the ends of the front of the 60 clod-cutter I, and said mouth-piece L is provided with a handle, L''', by means of which it is closed down after having been forced open against the pressure of the spring L'' by a stone or other obstacle that may accidentally 65 become mixed with the contents of the cylinder B and have been pressed down in the

press-box H. Thus by means of this movable and adjustable mouth-piece L, which yields and opens under the excessive pressure of a stone or other obstacle, the danger of a rupture of any part of the press-box H is avoided; but provided a large stone or obstruction, which, on account of its size, will not pass through the openings i of the clod-cutter I, becomes jammed between the mold M and clod-cutter I during the forward movement of the said mold M, then the point of the breaking rod R''' will break off, allowing the hook R to swing free and stop the motion of the arms S. The inner face of the said mouth-piece L is 80 provided with projecting blocks m''', that enter the spaces i' of the front plate, I', of the clod-cutter I, and overlap the front ends of the molds M.

In ordinary brick-machines the blocks m, for 85 closing the front of the clod-cutter, are each pivoted independently of the other, and each is operated by a separate spring; but such arrangement is objectionable on account of complication of parts and extreme liability of dis- 90 placement, while in the case of the mouth-piece L all the blocks m are attached to one plate, and all are operated by one spring.

N is the presser or plunger, consisting of an angle-plate fitted within the press-box H, and 95 provided at its ends and face with packing-strips n, that are pressed outward by the screws n' to prevent the escape of clay from the said press-box H at the joints between the said box H and the said presser or plunger N. The standard N' of said presser N extends upward 100 between the guides N'', that are bolted or otherwise secured to the front of the cylinder B, the projecting and inclined elbow of said standard N' being provided with a vertical 105 slot, n'', that extends through it from side to side, and the front of the said elbow being provided with perforations n''', for the reception of the pin n''', by means of which the length or throw of the pitman O is regulated, 110 and thereby the pressure of the presser N upon the clay in the press-box H. Said pin n''' is preferably made of cast-iron, so that if the presser N becomes jammed in the press-box H said pin n''' will break and prevent injury to 115 other parts by stopping the motion of the presser N, the said pitman O being made to straddle said standard N', while the pitman-pin O' passes through the slot n'' and rests on the pin n'''. The upper end of the pitman O 120 is movably connected with the arm or crank P by means of the crank-pin P', the other end of said arm or crank P being secured on the end of the horizontal shaft P'', that is journaled in the boxes P''', which are fastened to 125 the front of the cylinder B. The arm P''' connects the outer end of this shaft P'' with a crank-pin, P''', on an arm of the cog-wheel D'' on the shaft D, which shaft D is above and parallel with the shaft P'', and by means of 130 which motion is given to said shaft P'' and its connections.

On the opposite side of the device, pivoted on a stud, Q, which projects horizontally from a standard or pillow-block, C, is an elbow crank or arm, Q', whose round upper extremity, provided with a roller, o, is within reach of the eccentric D', and whose lower extremity connects with the upper end of the diagonal rod Q'', whose lower end adjustably connects, for the purpose of regulating the forward movement of the mold-driving arms S S, by means of nuts o', with the yoke or link Q''', that straddles and is connected with the rear and free end of the hooked arm R, whose front end is pivoted to the upward-projecting ears of the lever R', which lever R' is secured on the shaft R'', that extends from side to side of the base A, near the bottom thereof. Said lever R' extends rearward from the shaft R'', and has on its end a perforated lug, p, that is provided with vertical ears p', to hold the hooked arm R in position, and with a lever-screw, p''. Through this lug p is passed, from the front, a breaking rod, R''', of cast-iron or other suitable material, which rod R''' has its rear end extending an inch, or thereabout, beyond said lug p, and engaged in the hooked end of the hooked arm R, the said rod R''' being held in place by the lever-screw p''; hence it will be seen that the lever R' and its connections is moved by power transmitted through the rod Q'', link Q''', hooked arm R, and breaking rod R''', and that when the strain upon the projecting end of the breaking rod R''' breaks said rod R''' the hook R will swing freely and the lever R' and its connections cease to move.

On either end of the rocking shaft R'' are keyed the vertical arms S, that project upward on either side of the base A, and support between them the pushing-bar S', whose ends are fixed in rectangular boxes r, which boxes rest in the rectangularly-slotted heads of the said arms S, and said bar S' is adjustable forward or back by means of the set-screws r', that are entered through the heads of the arms S. This bar S' is designed to be adjustable parallel with the clod-cutter I, for pushing the mold M beneath the said clod-cutter I.

T represents a platform or table secured to the base A, and extending in front thereof, beneath and beyond the press-box H, for the purpose of supporting the molds M.

Journalled in the boxes T', which are vertically adjustable by means of the set-screws s s, are the rollers T'', which are set immediately beneath the press-box H and support the molds M, the faces of said rollers T'' being on a level with the face of the barred table T''', that is also fixed on said platform T in front of said rollers T''.

For operating this machine the motion given to the shaft E is transmitted through the bevel-gears E''' F to the mill-cylinder shaft F', whereby the brick materials thrown into said cylinder B are thoroughly mixed and tempered and forced out into the press-box H. At the same time motion is transmitted through the cog-

wheels E'', D'', arm P''', shaft P'', and crank P to the pitman O, the said parts moving in the directions indicated by their respective arrows, whereby at each revolution the presser 70 or plunger N is forced down on the brick material in the press-box H, to press said material through the clod-cutter I into the molds M, that are set on the rollers T''. At the same time, also, the motion is transmitted through 75 the eccentric D' to the elbow-crank Q', diagonal rod Q'', hooked arm R, breaking bar R''', and lever R' to the arms S, to cause the pushing-bar S' to move forward and push beneath the clod-cutter I, a mold, M, being successively 80 placed by the operator on the rolls T'', to be filled from the said clod-cutter I, and being successively pushed forward by the bar S', to be removed as fast as they are filled.

Having thus fully described my invention, 85 I claim as new and desire to secure by Letters Patent—

1. A brick-machine constructed substantially as herein shown and described, consisting of base A, cylinder B, provided with cross-bars 90 G'', vertical shaft F', provided with arms F'', and pivoted sweeps G, provided with stops g, press-box H, provided with presser or plunger N, having packing-strips n, and a perforated standard, N', provided with breaking 95 pin n''', clod-cutter I, provided with spring-regulated mouth-piece L, adjustable rod Q'' and its connected hooked arm R, lever R', and adjustable breaking-bar R''', arms S, and bar S', adjustable by set-screws r', and the operating mechanism thereof, as set forth.

2. In a brick-machine, the combination, with the cylinder B, of the base A, provided with flanged arches and legs A'' A', respectively, and feet A''', substantially as herein shown 105 and described, whereby said base is strengthened, as set forth.

3. In a brick-machine, the combination, with the cylinder-shaft F', provided with lugs f f, of the bolts f', and hinged sweeps or wipers G, 110 having stops g, substantially as herein shown and described.

4. In a brick-machine, the combination of the presser N, provided with standard N', and pitman O, provided with pin O', of the breaking pin n''', substantially as herein shown and described, whereby the rupture of other parts of the machine may be prevented, as set forth.

5. In a brick-machine, the combination, with the clod-cutter I, of the pivoted and spring-regulated mouth-piece L, provided with a series of blocks, m, substantially as herein shown, and for the purpose described.

6. In a brick-machine, the combination, with the cylinder-shaft F', of the independently-attached sweeps or wipers G, substantially as herein shown and described.

7. In a brick-machine, the combination, with the press-box H, of the plunger N, provided at its ends and face with packing-strips n, 130 pressed outward by screws n' to close the joints between the box H and plunger N, as set forth.

8. In a machine for making bricks, as a means for preventing the molds from moving when striking obstructions, the combination of the rocking arms S, pushing-bar S', lever R', provided with lug p, hooked arm R, adjustable breaking bar R'', yoke Q'', diagonal adjustable rod Q'', elbow-lever Q', and eccentric D', as and for the purpose set forth.

9. In a brick-machine, the combination, with cylinder-shaft F', of the independently-attached sweeps or wipers G, as shown and described.

WILLIAM E. TALLCOT.
